UNITED STATES PATENT OFFICE.

LOUIS STEINBERGER, OF BROOKLYN, NEW YORK.

HIGH-TENSION STRAIN-INSULATOR.

1,186,857.

Specification of Letters Patent. Patented June 13, 1916.

Application filed February 10, 1912. Serial No. 676,877.

To all whom it may concern:

Be it known that I, LOUIS STEINBERGER, residing at Brooklyn, in the county of Kings and State of New York, have invented certain new and useful Improvements in High-Tension Strain-Insulators, of which the following is a specification.

This invention relates to high tension strain insulators, such as are used in connection with lines for the transmission of high potential currents, and to the arrangement of such insulators in related series for the purposes of ordinary practice.

Among the objects which it is sought to attain may be stated the following: I. To provide insulator units of such structure that they may readily be united one to another either to form suspending means for a conductor or the like, or to constitute a multiple insulator for dead-ending purposes or the like. II. To provide insulator units whereby the foregoing object is attained, of such construction that high insulation value is secured, in whatever relation the units are united to each other. III. To provide insulator units as described, of such construction that when used individually or in some multiple relation, insulating values will be conserved because of adequate protection against moisture, dust, etc. IV. To provide suspension or dead-ending multiples which are as a whole rigid, of great insulating value, well protected against moisture, etc., and readily separable into the component individual units.

Other objects and aims of the invention, more or less broad than those stated above, will be in part obvious and in part specifically referred to in the course of the following description of the elements, combinations, arrangements of parts, and applications of principles, constituting the invention; and the scope of protection contemplated will appear in the claims.

In the accompanying drawings, in which I have shown a merely illustrative embodiment of the invention: Figure 1 represents a series of units connected to form a multiple suspension insulator, one of the individual units being shown in elevation; and the others in central vertical section; and Fig. 2 is an elevation partly in section of a multiple dead-ending or strain insulator visualizing my invention.

The individual units shown in the figures of the drawings are of similar construction,

so that a description of one of these units, as to its general features, will suffice.

Referring to the numerals on the drawings, 3 indicates the body portion of the insulator, which may be of general oblong conformation, provided with a hood 4 that springs from near one end of the insulator, which may be termed the top of the insulator, and extends in the general longitudinal direction of the insulator toward the opposite end thereof. The body portion of the insulator is further provided with openings 5 and 6, extending therewith from each end, there being a median partition 7 defining the inner ends of said openings. Preferably these openings are slot-like, and the planes of the lengths thereof cross each other. At each end of each slot there is an aperture 16' extending through the partition, the apertures that open from one slot passing through the material of the insulator on opposite sides of the other slot. At 8 and 9 are two metallic plates, disposed in the bottoms of the respective recesses 5 and 6, and having apertures registering with the apertures that extend from the bottom of the slot in which they are located. 10 indicates tension members which may take the form of U-shaped pieces, as shown, having their free ends threaded. These tension members are placed in position with their connecting pieces resting in the bottoms of the slots, on the bearing plates, and the arms of the tension members extending through the apertures of said bearing plates, and through the apertures that extend through the body of the insulator, the free ends of one tension member extending beyond one end of the insulator, and the free ends of the other tension member extending beyond the other end of the insulator, the connecting pieces of the tension members being of course insulated from each other by the partition that intervenes between the bottoms of the two slots. At the projecting ends of the tension members, respectively, are means whereby the ends of each tension member are connected together, and whereby the ends of the insulator may be connected to other insulators or devices. Preferably I provide cover plates 11, which cover the ends of the insulator and of course the respective slots 5 and 6, which, by the way, are filled with insulating material after the tension members have been put into place;

said cover plates being provided with aper-

tures through which the free ends of the tension members pass, and said cover plates having flanges which engage the body of the insulator. The cover plates are held in their relation to the ends of the insulator, and to their respective tension members by means of nuts 12 engaging the threaded ends of said tension members.

The general construction of insulator, and 10 the arrangement of tension member with respect thereto, is like that shown in the United States patent issued to me August 1, 1911.

For the purpose of connecting a series of 15 such units as have been described, to form a multiple suspension member such as shown in Fig. 1, the cover plate at the lower end of one insulator may be provided with a projecting threaded boss 14, and the top 20 cover plate of the next unit may be provided with an interiorly threaded socket member 15, in which said threaded boss would engage as shown in Fig. 1. However, I prefer that these cover plates may be 25 interchangeable, so that I can provide either or both ends of the insulator with a cover plate carrying a threaded boss or a cover plate carrying a threaded socket member.

In Fig. 2, I have shown two insulator 30 units such as already described, one of which is provided at what has been referred to as its top with a cover plate having a threaded boss and the other unit is provided at its top with a cover plate having a 35 threaded socket member. Thus the two units may be connected rigidly end to end, with their hoods extending in opposite directions. The bottom ends of the two insulators in Fig. 2 preferably both carry 40 cover plates provided with threaded bosses with which are engaged eyes 16 provided with threaded sockets which fit upon said threaded bosses. By means of these eyes the multiple insulator is supported.

45 It will be apparent that with insulator units of the general construction described, and with interchangeable cover plates, it is a matter of great ease to build up a multiple suspension insulator such as shown in 50 Fig. 1, or a multiple dead-ending insulator, such as shown in Fig. 2; while each unit is capable of use independently as desired.

Copies of this patent may be obtained for five cents each, by addressing the "Commissioner of Patents, Washington, D. C."

Having thus described my invention, what I claim as new and desire to secure by Letters Patent, is:

55 1. In an insulator, the combination with a body portion, having a pair of strain rods therein insulated from each other, of a pair of cover plates arranged one at each end of said body, said cover plates being of different formations for adapting them for co-operative relation with objects of different shapes, said cover plates being interchangeable with each other so as to adapt either end of said body for co-operative relation 60 with a given object, and means whereby said cover plates may be connected with either of said strain rods at will.

65 2. In an insulator, the combination with an elongated body portion having a strain rod therein projecting therefrom at one locality on said body and a second strain rod therein projecting therefrom at another locality on said body, of separately formed members attached one to the projecting portions of each of said strain rods, said separately formed members each having a part of a different shape from a corresponding part on another of said separately formed members so as to adapt said members for 70 attachment to objects of different shapes, and said members being interchangeable from one strain rod to another for the purpose of adapting the said different localities on said body for direct attachment with a 75 given object.

80 3. In an insulator, the combination with an elongated body portion, of a pair of attaching members therefor fixed one at each end of said body, one of said attaching members being formed with a threaded socket and the other of said attaching members being formed with a threaded stud, and said attaching members being interchangeable from one end of the body to the other, 85 all whereby either end of the body may be directly attached to a support comprising either a threaded socket or a threaded stud.

In testimony whereof I affix my signature in the presence of two witnesses.

LOUIS STEINBERGER.
